UNITED STATES PATENT OFFICE.

BERNARD GALLAGHER, OF LYNN, MASSACHUSETTS.

LAST-TRIMMING MACHINE.

SPECIFICATION forming part of Letters Patent No. 692,844, dated February 11, 1902.

Application filed October 19, 1900. Serial No. 33,581. (No model.)

To all whom it may concern:

Be it known that I, BERNARD GALLAGHER, a citizen of the United States, residing at Lynn, in the county of Essex and State of Massachusetts, have invented certain new and useful Improvements in Last-Trimming Machines; and I do hereby declare the following to be a full, clear, and exact description of the invention, such as will enable others skilled in the art to which it appertains to make and use the same.

This invention relates to last-trimming machines.

Boots and shoe lasts are now generally manufactured by means of automatic last-turning machines. Such machines, however, do not complete the formation of the last, but leave projections or stubs at the heel and toe portions, which must be subsequently trimmed off.

The object of my invention is to provide a machine for performing this operation, and more particularly to provide a machine for trimming off the projection at the heel, where-by the heels of the lasts will be trimmed off accurately and rapidly and without any attention on the part of the operator beyond the placing of the lasts in position in the machine and the removal of the trimmed lasts.

With this object in view my invention consists in providing a last-trimming machine with a suitable cutter, a jack for supporting a last and presenting the end of the last to the cutter, and connected mechanism acting automatically to relatively actuate the jack and cutter to transfer the point of contact of the cutter back and forth across the end of the last supported on the jack and to change the relative longitudinal positions of the jack and cutter.

My invention also consists in the devices and combinations of devices hereinafter described and claimed.

In carrying out my invention I have provided an organized machine which while particularly adapted for performing the function of trimming the heel of a last has certain features applicable to machines for performing other trimming operations and which are not limited to the particular machine illustrated in the drawings accompanying this application and hereinafter specifically described.

A preferred form of my invention is illustrated in the accompanying drawings, in which—

Figure 1 is a view in front elevation of a machine embodying the invention. Fig. 2 is a top plan view of the machine shown in Fig. 1, a portion of the top plate of the frame being broken away to show the underlying parts. Fig. 3 is a transverse sectional view taken on the line 3-3, Fig. 1. Fig. 4 is a detail sectional view of the parts supported on the shaft which actuates the mechanism for oscillating the jacks, the shaft being shown in elevation. Fig. 5 is a detail sectional view of a portion of one of the last-supporting jacks. Fig. 6 is a face view of those parts which are shown in Fig. 5; and Fig. 7 is a sectional view of one of the last-supporting jacks on the line 7-7, Fig. 1.

Referring to the drawings, in which like characters of reference indicate like parts, 1 indicates the frame of the machine, of any suitable construction, for supporting the operating parts; 2, the top plate or table of the frame; 3, a trimming-cutter mounted in bearings in the bracket 4, secured to the table 2 of the frame, and 5 a guide-roll rotatably mounted in the forked end of a rod 6, adjustably secured by means of a screw 7 in a bracket 8, secured to the table 2 of the frame.

9 represents a jack constructed to support a last and present the heel portion thereof to the cutter. For trimming the projecting stub at the heel portion of the last the cutter and jack are relatively actuated to cause the cutter to travel around the heel of the last, and means are provided for changing the relative longitudinal position of the cutter and jack and for moving the cutter and jack toward and from each other. In the construction shown in the drawings for producing these movements the cutter 3 is mounted in stationary bearings and rotated by means of a belt 10, passing over the pulley 11 on the shaft of the cutter, and the jack 9 is arranged to oscillate in front of the cutter to be moved longitudinally with relation thereto and to be moved toward and from the cutter.

For controlling the movements of the jack 9 toward and from the cutter a second jack 12 is provided, constructed to support a last-pattern and to present the heel portion of

the pattern to the guide-roll 5. The jacks 9 and 12 are rigidly secured to a horizontal shaft 46, journaled in the upper end of a frame 13, pivotally mounted upon a shaft 14, 5 journaled in journal-boxes 15 in the lower front portion of the frame. The frame 13 during the operation of the machine swings by its own weight toward the left, as shown in Fig. 3, and forces the last-pattern held by 10 the jack 12 against the roll 5 and the last held by the jack 9 against the cutter 3, the position of the last with relation to the cutter being determined by the contour of the heel portion of the last-pattern. The jacks 9 and 15 12 are substantially duplicates of each other, and each consists of a substantially rectangular frame, the central portion of one end of which is offset from the plane of the frame and provided with a collar fitting over and 20 secured to the end of the shaft 46 in the upper end of the frame 13. The other ends of the frames are also provided with offsets in line with the shaft 46.

Referring now more particularly to the jack 25 12, illustrated in detail in Figs. 5, 6, and 7, the last-pattern 16 is supported on the jack with the face of the heel resting against the offset portion of the frame with the center of the heel in axial alignment with the shaft 46, 30 to which the jack is secured. The ball of the last-pattern rests against a supporting-plate 17 secured by means of a screw 18 to a block 19, movable in a slot 20 formed in a guideway 21 secured in a slot in the end of the 35 frame of the jack by means of screws 22. The edges of the plate 17 bear against the surface of the guideway on each side of the slot 20, and by loosening the screw the plate can be adjusted for different sizes of patterns. 40 For securing the patterns in position a clamp arranged to engage the toe of the pattern is provided and also clamps arranged to engage the sides of the pattern. The toe-clamp is shown at 23 and consists of an angular block 45 secured by means of a screw-bolt 24 to a block 25, adapted to slide in the slot 20 of the guideway 21. For actuating the clamp 23 the block 25 is provided with a screw-threaded hole, through which passes a screw-threaded rod 26, which also passes loosely through the block 19, to which the plate 17 is secured. The outer end of the rod 26 is journaled in a block 27, screwed into the outer end of the guideway 21, being held from longitudinal 55 movement in the block by means of a collar or flange 28 on the rod 26 bearing against the inner end of the block 27 and a nut 29 on the outer end of the rod bearing against the outer end of the block 27. A hand-wheel 30 60 is secured to the outer end of the rod 26, by means of which the rod can be rotated to move the clamp 23 into engagement with the toe of the pattern. The clamps, which bear against the sides of the pattern, are four in number, three being arranged to bear 65 against the under side of the pattern and one against the upper side of the pattern.

These clamps consist of screw-threaded rods provided with heads or bearing-faces to engage the pattern. Two of these clamps 31 70 and 32 project upwardly through blocks 33, provided with dovetail grooves engaging a guide on the lower side of the jack-frame, the blocks being adjustably held on the guides by means of set-screws 34. The clamp 31 75 engages the pattern near the heel portion and the clamp 32 engages the pattern near the top or ankle portion, the adjustable connection of the blocks with the jack-frame enabling the clamps to be adjusted longitudinally of the frame and transversely to the plane of the bottom of the last-pattern for different sizes of patterns. The clamp 35 projects upwardly through a block 36, provided with a slot engaging a guideway projecting from the end of the jack-frame, the block being adjustably secured to the guide by means of a set-screw 37. The clamp 35 bears against the under side of the pattern, near its toe portion, the adjustable connection of the block 36 with the frame allowing the clamp to be adjusted transversely to the frame to accommodate patterns of different lengths. The upper clamp 38 is mounted in the same manner as the clamps 31 and 32, so 90 as to be adjustable longitudinally of the jack-frame. The clamping-surface 39 of the clamp 38 is secured to the lower end of the screw-threaded rod by means of a ball-and-socket joint, whereby the head can adapt itself to 100 the surface of the pattern, and the upper end of the screw-threaded rod is provided with a handle or knob 40, by means of which the rod can be operated.

In practice the clamps 31, 32, and 35 are 105 set so that a pattern placed thereon will be properly centered in the jack, and the clamp 38 alone is operated to allow the removal of one pattern and the insertion of another. For centering the pattern in the jack I preferably 110 provide centering devices adapted to engage the heel and the top of the pattern. As shown, the centering device for the heel consists of a yoke 41, carried at the outer end of two rods 42, arranged to slide in a collar 43, secured 115 to a spindle 44, projecting from the jack-frame in axial alignment with the shaft to which the jack is secured. The device for engaging the top of the pattern consists of a fork 45, arranged to slide in a hole formed in the end 120 of the jack-frame or in the shaft to which the frame is secured. In centering the pattern the yoke 41 is pulled out to the position shown in Fig. 5, the pattern placed in the position shown in dotted lines in said figure, and the 125 toe-clamp 23 actuated to engage the toe of the pattern. The fork 45 is now pulled out into the position shown in dotted lines, Fig. 1, the sides of the fork engaging the top edges of the pattern. The pattern being thus held in 130 position, the clamps 31, 32, and 35 are moved into engagement therewith and the yoke 41 and fork 45 pushed back from contact with the pattern, the yoke 41 moving transversely

to the plane of the bottom of the last-pattern. The toe-clamp 23 and the side clamps 31, 32, and 35 now form guides upon which the pattern can be placed in correct position and 5 clamped thereon by means of the clamp 38. The clamping and centering devices of the jack 9 are the same in all respects as those just described. For the jack 9 the toe-clamp, however, is arranged at the end of the jack- 10 frame next to the frame 13 instead of at the end remote therefrom, as in the pattern-jack.

As a means for oscillating the jacks the shaft 46, to which the jacks are secured, has fastened thereto between the bearings for 15 the shaft an arm 47, connected by means of a rod 48 and strap 49 to an eccentric 50, secured to the shaft 14. The shaft 14 has secured thereto a pulley 51, over which passes a driving-belt 52, said belt also passing over 20 a pulley 53 on the driving-shaft 54, journaled in boxes pivotally supported in yokes 55, secured to brackets 56, extending rearwardly from the upper portion of the machine-frame. The driving-shaft 54 is driven by means of a 25 belt 57, passing over a pulley 58, secured to the shaft.

For moving the jacks longitudinally with relation to the pattern-guide and cutter the machine shown in the drawings is provided 30 with mechanism for feeding the frame 13 laterally. This mechanism consists of a screw-threaded sleeve 59, loosely surrounding the shaft 14 and free to revolve independently thereof, said sleeve being provided at one end 35 with a pulley 60, over which passes a belt 61, the belt also passing over a pulley 62 on the driving-shaft 54. The other end of the sleeve 59 abuts against a hub of the frame 13. (See more particularly Fig. 4.) A screw-threaded 40 block or nut 63, bolted to the end of the lever 64, pivoted to one of the journal-boxes 15 for the shaft 14, engages the upper surface of the sleeve 59. The frame 13 is provided with laterally-extending hubs 65 and 66. The hub 45 of the pulley 51, which is secured to the shaft 14, abuts against the end of the hub 65, the hub of the eccentric 50 abuts against one end of the hub 66, and the end of the sleeve 59 abuts against the other end of the hub 66. 50 By this construction as the sleeve 59 is revolved the sleeve will be moved longitudinally through the nut 63 and will carry with it the frame 13, the shaft 14, and the parts secured thereto. For moving the driving-shaft 54 longitudinally with the shaft 14 in order to 55 keep the pulleys over which the belts 52 and 61 pass in alignment an arm 67 is secured to the hub 65 of the frame 13, said arm extending to the shaft 54 and being provided with 60 a segmental end which is received in the groove of a collar 68, secured to the driving-shaft 54.

At the end of the trimming operation it is desirable that the mechanism for moving 65 the frame 13 laterally be automatically thrown out of operation, and as a means for accomplishing this result the machine of the draw-

ings is provided with mechanism which will now be described.

Pivoted in the lower part and at the rear 70 of the frame are two levers 69, extending to the front of the machine and connected by means of the treadle 70. Pivoted to the levers 69 and extending upwardly therefrom are links 71, connected at their upper ends by 75 means of a rod 72, and extending upward from about the middle point of the rod 72 is an arm 73, to which is pivotally connected a lever 74, pivoted on a bracket depending from the table 2 of the machine-frame, and provided at its 80 outer end with a weight 75, the tendency of the weight through the described connections being to raise the lever 69 and treadle 70. Pivoted to the lever 64 is a lever 76, the lower end of which is bent or otherwise formed to 85 surround one of the levers 69, and the upper end of which is adapted to engage, when the treadle is in its lowest position, a shoulder or a notch on a plate 77, secured to the table 2 of the machine-frame. The lever 76 is pressed 90 into engagement with the notch of the plate 77 by means of a spring 78, one end of which engages the upper end of the lever and the other end of which is secured to a bracket extending upward from the lever 64. The 95 lever 76 when in engagement with the notch in the plate 77 serves as a locking means for holding the lever 69 and treadle 70 depressed and the nut 63 in engagement with the threaded sleeve 59. Adjustably secured on 100 the sleeve 59 by means of the set-screw 79 is a collar 80, which as the sleeve 59 moves to the left, as viewed in Fig. 1, contacts with the lower end of the lever 76 and moves the upper end of the lever out of engagement 105 with the notch in the plate 77. When the lever 76 is thus released, the weight 75, through the described connections, acts to raise the levers 69 and treadle 70 and through the lever 76 raise the nut 63 from engagement 110 with the sleeve 59.

The frame 13 is movable toward and from the guide and cutter, as has been stated, and for moving the frame back to separate the jacks from the cutter and guide at the end 115 of the trimming operation the following mechanism is provided: Referring more particularly to Fig. 3, 81 designates a slotted plate or block, the slot in which engages a groove in a collar 82, secured to a rod 83, mounted in bearings in the upper part of the machine-frame and free to move longitudinally therein. Secured to one side of the plate 81 is a plate 84, provided with an inclined slot, through 120 which passes a headed stud 85, projecting 125 from the side of the frame 13. The plate 84 is adjustably secured to the plate 81 by being pivoted thereto at its lower end and by being connected therewith at its upper end by means of a strap 86, one end of which is pivoted to the plate 84 and the other end of which is secured to the plate 81 by means of a bolt passing through a slot in the end of the strap. As the plate 81 is raised it will be 130

held from lateral movement by the engagement of its slot with the grooved collar 82, and the inclined slot of the plate 84 acting against the stud 85 will swing the frame 13 backward on its pivot to move the jacks away from the pattern-guide and cutter. The slot in the plate 84 is wider at its upper portion, as shown, whereby sufficient lost motion is provided for to allow the frame 13 to move 10 backward and forward during the trimming operation. Extending downward from the plate 81 is a rod 87, the lower end of which is provided with friction-rolls 88, between which a rod 89 passes, connecting the levers 69. By this means as the lever 69 and treadle 70 rise when released by the mechanism hereinbefore described the plates 81 and 84 are actuated to move the frame 13 away from the pattern-guide and cutter.

When the frame 13 is moved away from the pattern-guide and cutter at the end of the trimming operation, it is desirable that the mechanism for oscillating the jacks should be thrown out of operation to allow the removal of the trimmed last and the insertion of an untrimmed last. For accomplishing this result the belt 52 is provided with a belt-tightener, which is actuated from the mechanism for moving the frame 13 away from the guide and cutter. This belt-tightener consists of a loose pulley or roll 90, carried on one end of a lever 91, pivoted to the arm 67, and connected at its other end by means of a link 92 with the rod 87. The result of this construction is that as the rod 87 rises the lever 91 is swung about its pivot and the belt-tightener roll 90 moved away from the belt 52, which is thereby slackened and allowed to run loosely over the pulley 51. The plates 81 and 84 and the rod 87 move laterally with the frame 13, and to insure such movement of the lower end of the rod 87 the lower end of the rod passes between a forwardly-projecting portion of the arm 67 and a strap secured thereto by bolts, as is clearly shown in Fig. 1 and 3.

The machine shown in the drawings is also provided with means for returning the frame 13 and the parts which are laterally movable therewith to their original positions. This mechanism consists of a shaft 93, journaled in the lower part of the machine-frame, provided with a screw-threaded portion 94 and constantly rotated by means of a belt 95, passing over a pulley 96, secured to the shaft. The arm 67 is provided with a downwardly and rearwardly extending portion 97, having bolted thereto a screw-threaded block or nut 98, adapted to engage the screw-threaded portion 94 of the shaft 93. As has been stated, the arm 67, with which the portion 97, carrying the nut 98, is integral, is rigidly secured to the hub 65 of the frame 13, and consequently moves therewith. When the frame 13 is moved away from the pattern-guide and cutter, as has been hereinbefore described, the portion 97 of the arm 67 is moved sufficiently

to cause the nut 98 to engage the screw-threaded portion 94 of the shaft 93, and when so engaged the frame 13 and the parts laterally movable therewith will be returned to their original positions.

It will be seen that the bearings in the frame 13 for the shaft 46, to which the jacks are secured, are comparatively short and are situated between the two jacks. For additionally supporting the jacks I provide arms 99, 100, and 101, secured to the rod 83, and connect the arms 99 and 101 by means of links or rods 102 and 103 to the spindle 44 of the jack 12 and a similar but shorter spindle of the jack 9, said spindles being in axial alignment with the shaft 46 and passing through bearings in the end of the rods 102 and 103. The arm 100 is connected in a similar manner to the shaft 46 by means of a rod 104, and a rod 105, provided with journal-boxes at its ends, also connects the spindle 44 with the shaft 14.

The journal-boxes 15 are pivotally mounted 90 in yokes 106, adjustable vertically in brackets secured to the lower part of the machine-frame, as clearly shown in Fig. 1. By this construction the shaft 14 can be brought into alignment with the other shafts and the shaft 95 is allowed to move longitudinally through the journal-boxes without binding. The journal-boxes 15 are situated at opposite ends of the machine, and for supporting the shaft between the boxes a collar 107, surrounding the hub 66 of the frame 13, is provided, (see Figs. 1 and 4,) said collar being supported from the table 2 of the machine-frame by means of a rod 108, projecting upwardly from the collar and secured to a block 109, sliding on a guide 105 on the table 2.

For still further connecting the frame 13 and rod 83 to cause them to move laterally in unison the rod 83 has secured thereto an arm 110, which projects between the frame 13 and a strap 111, secured to the side of the frame 13 by suitable bolts, as is shown in Figs. 1 and 3.

The operation of the machine above described is as follows: The pattern and last having been centered and clamped in position 115 in the jacks, as has already been described, the treadle 70 is depressed, thereby through the lever 76 depressing the lever 64 and bringing the nut 63 into engagement with the threaded sleeve 59, the upper end of the lever 120 76 being forced into the notch in the plate 77 and locking the treadle in its depressed position. At the same time the plates 81 and 84 through the rod 87, rolls 88, and rod 89 are moved down, thereby forcing the frame 13 125 toward the pattern-guide and cutter. As the rod 87 is moved down the belt-tightening pulley 90 is through the lever 91 and link 92 brought into contact with the belt 52 to thereby cause the same to rotate the pulley 51 and the shaft 14. The jacks are now oscillated by means of the eccentric 50 and connections, as above described, and the frame 13, carrying the jacks, moved laterally by the engagement

of the threaded sleeve 59 with the nut 63. As the jacks are oscillated and moved longitudinally past the guide and cutter the movement of the frame 13 toward and from the guide 5 and cutter will be controlled by the engagement of the guide-roll 5 with the heel portion of the pattern, and the heel portion of the last clamped in the jack 9 will be trimmed to the exact shape of the heel portion of the pattern. The collar 80 having been properly adjusted on the sleeve 59, at the end of the trimming operation the collar will contact with the lever 76 to disengage the lever from the notch in the plate 77, and thereby allow the treadle 15 to rise. As the treadle rises the nut 63 will be disengaged from the sleeve 59, the frame 13 will be moved away from the pattern-guide and the cutter, the belt-tightener 90 will be moved away from the belt 52, and the nut 98 20 will be thrown into engagement with the screw-threaded portion 94 of the shaft 93 and the parts returned to their original position, as has been already described.

For releasing the treadle manually at any 25 point in the trimming operation a hand-lever 112 is provided, pivoted at the lower end of the plate 77 and provided with a pin 113, arranged to engage the upper end of the lever 76 and disengage it from the notch in the 30 plate 77. A weight 114 at the end of the hand-lever holds it normally in the position shown in Fig. 1.

While the machine above described embodies my invention in the best form at present known to me, it is to be understood that 35 my invention is not limited to the details of construction shown and described, but may be embodied in many different constructions without departing from the spirit thereof.

Having thus described my invention, I 40 claim as new and desire to secure by Letters Patent of the United States—

1. A last-trimming machine, having, in 45 combination, a cutter, a jack constructed and arranged to support a last and present the end of the last to the cutter, and connected mechanism acting automatically to relatively actuate the jack and cutter to transfer the point of contact of the cutter back and forth across 50 the end of the last supported on the jack and to change the relative longitudinal positions of the jack and cutter, substantially as described.

2. A last-trimming machine, having, in 55 combination, a cutter, a jack constructed and arranged to support a last and present the end of the last to the cutter, connected mechanism acting automatically to relatively actuate the jack and cutter to transfer the point of contact of the cutter back and forth across the end of the last supported on 60 the jack, and to change the relative longitudinal positions of the jack and cutter, and means for automatically returning the parts to their initial 65 position, substantially as described.

3. A last-trimming machine, having, in 70 combination, a cutter, an oscillating jack for

supporting a last and presenting the end of the last to the cutter, and connected mechanism acting automatically to change the relative longitudinal positions of the jack and cutter and oscillate the jack, substantially as described.

4. A last-trimming machine, having, in combination, a cutter, an oscillating jack for 75 supporting a last and presenting the end of the last to the cutter, connected mechanism acting automatically to change the relative longitudinal positions of the jack and cutter and oscillate the jack, and means for automatically returning the parts to their initial position, substantially as described.

5. A last-trimming machine, having, in combination, a cutter, a jack for supporting a last and presenting the end of the last to 85 the cutter, mechanism for oscillating the jack, mechanism for moving the jack longitudinally, and means for automatically returning the jack to its initial position, substantially as described.

6. A last-trimming machine, having, in combination, a cutter, a jack for supporting a last and presenting the end of the last to the cutter, and connected mechanism acting automatically to oscillate the jack and move it 95 longitudinally, substantially as described.

7. A last-trimming machine, having, in combination, a cutter, an oscillating jack for supporting a last and presenting the end of the last to the cutter, mechanism for oscillating the jack, mechanism for moving the jack longitudinally, and means for automatically throwing said mechanisms out of operation, substantially as described.

8. A last-trimming machine, having, in combination, a cutter, an oscillating jack for supporting a last and presenting the end of the last to the cutter, said cutter and jack being movable toward and from each other, means for controlling such movements, means for oscillating the jack, means for changing the relative longitudinal positions of the jack and cutter, and means for automatically separating the jack and cutter, substantially as described.

9. A last-trimming machine, having, in combination, a cutter, a jack constructed and arranged to support a last and present the end of the last to the cutter, said cutter and jack being movable toward and from each other, 120 means for controlling such movements, connected mechanism acting automatically to relatively actuate the jack and cutter to transfer the point of contact of the cutter back and forth across the end of the last supported on 125 the jack, and to change the relative longitudinal positions of the jack and cutter, and means for automatically throwing said mechanism out of operation and separating the jack and cutter, substantially as described.

10. A last-trimming machine, having, in combination, a cutter, an oscillating jack for supporting a last and presenting the end of the last to the cutter, mechanism for oscillat-

ing the jack, mechanism for moving the jack longitudinally, and means for automatically throwing the mechanism for oscillating the jack out of operation and separating the jack and cutter, substantially as described.

11. A last-trimming machine, having, in combination, a cutter, an oscillating jack for supporting a last and presenting the end of the last to the cutter, mechanism for oscillating the jack, mechanism for moving the jack longitudinally, and means for automatically throwing the mechanism for moving the jack longitudinally out of operation and separating the jack and cutter, substantially as described.

12. A last-trimming machine, having, in combination, a cutter, an oscillating jack for supporting a last and presenting the end of the last to the cutter, mechanism for oscillating the jack, mechanism for moving the jack longitudinally and means for automatically throwing said mechanisms out of operation and separating the jack and cutter, substantially as described.

13. A last-trimming machine, having, in combination, a cutter, a jack constructed and arranged to support a last and present the end of the last to the cutter, said cutter and jack being movable toward and from each other, means for controlling such movements, connected mechanism acting automatically to relatively actuate the jack and cutter to transfer the point of contact of the cutter back and forth across the end of the last supported on the jack and to change the relative longitudinal positions of the jack and cutter, means for automatically separating the jack and cutter, and means for automatically returning said parts to their initial position, substantially as described.

14. A last-trimming machine, having, in combination, a cutter, an oscillating jack for supporting a last and presenting the end of the last to the cutter, said cutter and jack being movable toward and from each other, mechanism for oscillating the jack, mechanism for moving the jack longitudinally, means for automatically throwing said mechanisms out of operation, and means for automatically returning said jack to its initial position, substantially as described.

15. A last-trimming machine, having, in combination, a pattern-guide, a cutter, a frame movable toward and from the cutter and guide, jacks pivotally mounted in the frame, one of said jacks constructed to support a last-pattern with its end bearing against the pattern-guide, the other of said jacks constructed to support a last with its end bearing against

the cutter, and connected mechanism acting automatically to oscillate the jacks and move the frame laterally, substantially as described.

16. A last-trimming machine, having, in combination, a pattern-guide, a cutter, a frame movable toward and from the guide and cutter, two jacks pivotally mounted in the frame constructed to support a last-pattern and a

last, respectively, a shaft upon which said frame is pivoted, mechanism driven from the shaft for oscillating the jacks, and means for moving the frame laterally comprising a screw-threaded sleeve surrounding said shaft and bearing against said frame, means for rotating the sleeve and a screw-threaded nut engaging said sleeve, substantially as described.

17. A last-trimming machine, having, in combination, a pattern-guide, a cutter, a frame movable toward and from the guide and cutter, two jacks pivotally mounted in the frame constructed to support a last-pattern and a last, respectively, a shaft upon which said frame is pivoted, mechanism driven from the shaft for oscillating the jacks, driving mechanism for the shaft, means for moving the frame laterally comprising a screw-threaded sleeve surrounding said shaft and bearing against said frame, means for rotating the sleeve and a screw-threaded nut engaging said sleeve, and means for automatically disengaging the nut and sleeve and throwing the driving mechanism for the shaft out of operation, substantially as described.

18. A last-trimming machine, having, in combination, a pattern-guide, a cutter, a frame movable toward and from the guide and cutter, two jacks pivotally mounted in the frame constructed to support a last-pattern and a last, respectively, a shaft upon which said frame is pivoted, mechanism driven from the shaft for oscillating the jacks, mechanism for moving the frame laterally, means for returning the frame, comprising a screw-threaded shaft and a nut carried by the frame adapted to engage said shaft, and means for automatically throwing the mechanism for moving the frame laterally out of operation and for moving the nut into engagement with the shaft, substantially as described.

19. A last-trimming machine, having, in combination, a frame, a clamp movable longitudinally of the last when in position on the jack and arranged to extend over and engage the toe of the last and clamps for engaging the sides of the last, substantially as described.

20. In a last-trimming machine, a jack comprising a frame, and clamps for engaging the sides of the last adjustable on the frame transversely to the plane of the bottom of the last when in position on the jack, substantially as described.

21. In a last-trimming machine, a jack comprising a frame, clamps for engaging the last and a heel-gage for centering the last movable transversely to the plane of the bottom of the last when in position on the jack, substantially as described.

22. In a last-trimming machine, a jack comprising a frame, clamps for engaging the last, and last-centering gages shaped to engage opposite sides of the heel and top portions of the last movably mounted on the frame, substantially as described.

23. A last-trimming machine, having, in combination, a pattern-guide, a cutter, a

frame movable toward and from the guide and cutter, two jacks pivotally mounted in the frame constructed to support a last-pattern and a last, respectively, a shaft upon which said frame is pivoted, mechanism driven from the shaft for oscillating the jacks, driving mechanism for the shaft, means for moving the frame laterally comprising a screw-threaded sleeve surrounding said shaft and bearing against said frame, means for rotating said sleeve and a screw-threaded nut engaging said sleeve, means for returning the frame comprising a screw-threaded shaft and a nut carried by the frame, adapted to engage said shaft, mechanism for moving the frame away from the guide and cutter, a

treadle, a locking device for the treadle, means for raising the treadle, intermediate connections for disengaging the nut and sleeve, throwing the driving mechanism for the shaft out of operation, moving the frame away from the cutter and guide and engaging the nut and screw-threaded shaft when the treadle rises, and means for automatically releasing the treadle, substantially as described. 25

In testimony whereof I affix my signature in presence of two witnesses.

BERNARD GALLAGHER.
